UNITED STATES PATENT OFFICE.

JAMES B. WAGG AND JOHN A. JOHNSON, OF APPLETON, WISCONSIN, ASSIGNEES OF ONE-THIRD TO WILLIAM L. WAGG, OF APPLETON, WISCONSIN.

GUARD FOR CALENDERING-MACHINES.

1,102,109.

Specification of Letters Patent.

Patented June 30, 1914.

Application filed October 4, 1913. Serial No. 793,433.

To all whom it may concern:

Be it known that we, JAMES B. WAGG and JOHN A. JOHNSON, citizens of the United States, residing at Appleton, in the county 5 of Outagamie and State of Wisconsin, have invented new and useful Improvements in Guards for Calendering-Machines, of which the following is a specification.

The present invention relates to calendering machines, and it proposes, briefly, an attachment for machines of the class or character indicated which is designed to prevent 10 injury to the workmen during manipulation of the paper.

In the types of calendering machine in general use, a series of alternating chilled iron and paper-filled rolls are mounted in superposed relation in vertical standards, to form what is ordinarily termed the "stack," 15 it being the duty of certain mill operatives to pass the webs of paper by hand through these rolls to impart the desired high finish thereto, and as the rolls are of very considerable size and weight, there is always 20 danger of the operatives' hands or fingers being caught between the rolls and crushed. It has been proposed to protect the operatives by equipping the stacks with specially 25 constructed doctors, which, in addition to their usual function of preventing adhesion 30 of the paper to the rolls, serve to some extent as guards by being extended partly over the rolls; but in actual practice these devices have proven objectionable and unsatisfactory, since the blade portions thereof are 35 liable to injure the delicate surfaces of the paper-filled rolls.

To overcome the defect just specified, and, at the same time, to provide complete protection 40 for the operatives, we contemplate using, in accordance with our invention, a series of guards in the form of straps which are located at the nip of the rolls, where the paper is fed inwardly, and are so constructed as to provide for the easy passage 45 of the paper between the rolls, while effectively preventing entrance of the hands or fingers therebetween.

We also contemplate a further improvement 50 for the guards in that we provide them with sight openings which are disposed exactly in line with the nip of the rolls, when the guards are in place, and thus enable the operatives to examine the 55 surface contact of the paper with the rolls, a

feature which was impossible with the doctor-guards.

Finally, we aim to provide a guard which is extremely simple in its construction, and, therefore, capable of being manufactured at 60 a minimum cost, and which, moreover, may be readily applied to any of the conventional types or makes of calendering machine now on the market.

An embodiment of the invention is illustrated in the accompanying drawing, whereof:—

Figure 1 is a fragmental front elevation of a calendering machine equipped with the improved guards; Fig. 2 is a vertical section taken on line 2—2 of Fig. 1; and Fig. 3 is a perspective view of one of the guards.

The calendering machine depicted in the said drawing is of conventional type and, therefore, requires no extended description. 75 It consists, as is usual, of alternating chilled iron and paper-filled rolls 5 and 6 mounted in superposed relation in vertical standards 7 and 8, and constituting the stack, the rolls being rotated through the agency of suitable 80 driving mechanism, (not shown). The paper web 9 is fed through the stack by the operatives, and passes over and between the rolls in the ordinary manner.

The improved guards 10, which present 85 the most important features of the invention, as previously stated, are located at the points where the paper passes inwardly through the nips of adjacent rolls. They are here represented as consisting, each, of a metal 90 strap, which is arranged in horizontal position between the standards and is bolted or otherwise fastened to the inner faces thereof at its laterally-bent ends 11. The body portion 12 of the strap is of V- or angle-section, as shown in Fig. 2, the V or angle projecting inwardly toward the nip of the rolls and having its apex or ridge line directly opposite and parallel with the line of nip. The two wings or members resulting from this formation are of equal width, and are bowed or curved outwardly away from the rolls, thereby providing a space 95 through which the paper can readily pass between the rolls, while yet completely preventing the hands or fingers of the operatives from being drawn therebetween. To enable the surface contact of the paper with the rolls to be observed, each guard is provided with a longitudinal sight opening 100

105

110

which is formed therein at the ridge or apex of the V, so as to exactly parallel the nip of the rolls. In the construction illustrated, the opening is shown as comprising a series of three alining slots 13, but it is obvious that such number is purely arbitrary, and may be either increased or decreased. As the paper is fed between the rolls, first in one direction and then in the other, alternately, it will be understood that the guards are arranged at both sides of the stack.

We claim:—

1. A guard for calendering machine rolls adapted for arrangement opposite the nip of adjacent rolls and having a sight opening formed through it.
2. A guard for calendering machine rolls adapted for arrangement opposite the nip of adjacent rolls and having a sight opening formed through it which directly parallels the said nip.
3. A guard for calendering machine rolls adapted for arrangement opposite the nip of adjacent rolls and having a longitudinal sight opening formed through it which directly parallels the said nip and comprises a plurality of alining slots.
4. A guard for calendering machine rolls comprising a strap adapted for arrange-

ment opposite the nip of adjacent rolls and embodying upper and lower longitudinal wings disposed at an angle to each other, the apex of which angle projects inwardly toward the said nip, one of said wings extending over the adjacent roll and being curved outwardly away from the same.

5. A guard for calendering machine rolls comprising a strap adapted for arrangement opposite the nip of adjacent rolls and embodying upper and lower longitudinal wings disposed at an angle to each other, the apex of the angle projecting inwardly toward the said nip, and being formed with a longitudinal sight opening which parallels the said nip.

6. A guard for calendering machine rolls comprising a strap adapted for arrangement opposite the nip of adjacent rolls and having a body portion of angle- or V-section which projects inwardly toward the said nip and is provided with a sight opening.

In testimony whereof we have hereunto set our hands in presence of two subscribing witnesses.

JAMES B. WAGG.
JOHN A. JOHNSON.
